US00D704688S

(12) United States Design Patent
Reivo et al.

(10) Patent No.: US D704,688 S
(45) Date of Patent:  May 13, 2014

(54) HANDSET REAR COVER

(75) Inventors: Tuomas Reivo, Helsinki (FI); Terence Tan Han Yang, Helsinki (FI)

(73) Assignee: Nokia Corporation, Espoo (FI)

() Term: 14 Years

(21) Appl. No.: 29/431,088

(22) Filed: Sep. 4, 2012

(51) LOC (10) Cl. 14-03

(52) U.S. Cl.

USPC D14/250

(58) Field of Classification Search

USPC ..... D14/138 AD, 138 C, 138 G, 203.7, 230, D14/238.1, 240, 247, 248, 250, 253, 341, D14/345, 346, 439, 440, 447; D13/103, D13/107, 119; D3/201, 218, 269, 273, 303; 206/320; 220/662; 361/679.27, 753, 361/737; 455/456.1, 575.1, 575.4, 575.8

(57) CLAIM

The ornamental design for a handset rear cover, as shown and described.

DESCRIPTION

FIG. 1 is a perspective view of a handset rear cover showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines of the handset and the unshaded regions therein are for illustrative purposes only and form no part of the claimed design.

1 Claim, 5 Drawing Sheets
